L. JOHNSON

INSULATED WIRE STRIPPER

Filed Sept. 10, 1924

FIG. 2

INVENTOR:
Lawrence Johnson
BY: Oliver O. Martin
HIS ATTORNEY.

UNITED STATES PATENT OFFICE.

LAWRENCE JOHNSON, OF CHICAGO, ILLINOIS, ASSIGNOR TO JOHNSON & WENTINK, OF CHICAGO, ILLINOIS, A PARTNERSHIP CONSISTING OF LAWRENCE JOHNSON AND ALFRED N. WENTINK.

INSULATED-WIRE STRIPPER.

Application filed September 10, 1924. Serial No. 736,843.

This invention has relation to means for removing the insulation from the ends of electrical light and power conductors.

Various machines of this type have been devised, of which some have reached the market. In all such machines, so far as I am advised, two operations are required in order to strip the insulation from the end of an insulated wire. In some of these machines the stripping knives commence to close automatically on the insulation when the machine begins to rotate, but it is necessary to stop the machine in order to open the knives, so as to be able to insert another wire end. Others run continuously, but on such an extra hand or foot operation is required to close the knives on the conductor, and again to open them.

The principal object of the present invention is the provision of a fully automatic machine, by which I mean a continuously running machine, into which it is only necessary to push the wire end the desired distance and quickly to withdraw it stripped of its insulation. Such a machine is hereinafter described and illustrated in the appended drawing, of which:

Fig. 1 is a sectional side elevation of a structure embodying the invention,

Fig. 2 is a corresponding front elevation of the device with parts broken away for the sake of clearness.

The invention in the form illustrated is supported on and driven by an electric motor 1, on the armature shaft of which is clamped a bifurcated head in any suitable manner, as by a set screw 3. This head, 2, supports a pair of oscillatory frames 4 and 5, mounted to swing axially upon suitable pivots 6, and these frames are shaped to receive a pair of knives 10 and 11, the opposed cutting edges of which are directed toward the axis of the head. Across the front of the bifurcated head is rigidly mounted a strip 12, and this strip is centrally perforated to receive a guide bushing 13.

The foregoing short description is sufficient to explain the operation of my device. In order to strip the insulation 15 from a piece of wire 14 it is in the first instance necessary to start the motor, thereby causing the head 1 to rotate. Now it is noticed that the portion of the knife frames lying outside the pivots 6 are larger and therefore heavier

than their inner portions, as a consequence of which these frames are urged by centrifugal force into the upright position indicated in dotted outline, and in this position they will remain until the motor again is stopped or until the wire 14 is pushed through the guide 13 and against the yielding inner ends of the knives 10, 11. As the knives will yield to the pressure of the wire, the latter is carried forward between the knife edges as far as desired, as shown in dotted outline at 16, compelling the knives to take the position shown in full outline. But the moment the operator pulls on the wire to withdraw it it is to be observed that the knives will begin to right themselves again, and a continued pull on the wire permits the knives to resume their upright position, thereby bringing their cutting edges sufficiently together to penetrate the insulation of the wire, which then is fully withdrawn, leaving the stripped insulation free to fly out to one side. This single operation needs to take only two seconds.

In order that the knives may cut evenly it is well to combine them in such a manner that one will follow the other, and this may be accomplished in the manner shown in the drawing to comprise a pair of gear segments 17, 18 rigidly mounted on the sides of the knife frames 4 and 5. With such intermeshing segments the knives are compelled to move together and to cut evenly. The knives should be longitudinally movable in their supports, in order that they may be adjusted to operate on conductors of various diameters, and this may conveniently be done by seating screws 19, 20 in screw threads cut into the outer ends of the knife brackets, and by providing these screws with annular flanges 21, 22, which in turn fit into transverse slots 23, 24 in the outer ends of the knives. After once adjusted the knives are clamped in position by set screws 25 and 26.

The device of my invention is not required to rotate at any great speed, in fact it will function perfectly when rotated by hand, but where it is mounted to rotate with the armature shaft of an electric motor, it is compelled to operate at a much greater speed than necessary. And as it is very dangerous to have such high speed structure exposed while in rotation, I have provided a suitable stationary cover 30, which completely

encompasses the head. This cover is shown forced on to the bearing and commutator casing of the motor, but it may, of course, be supported in any other suitable manner.

5 It is only necessary that one or more large openings 31, 32 be made in the bottom of the cover, in order to permit the stripings to drop out of the way.

In conclusion I wish to state that I may 10 provide a pair of springs 40, 41, which will operate to return the frames 4 and 5 to their radial position, in which case the centrifugal force need not be depended upon. I may also make provision for a gauge 15 to determine the length of the stripping, and such gauge may take the form shown in the drawing to comprise an angle bracket 34, held by a screw 35, and provided with a graduated scale 33, by means of which 20 the gauge may be set to a predetermined length. I also reserve the right to introduce other modifications, so long as I remain within the scope of the invention, as hereinbefore outlined.

25 I claim:

1. In a wire stripper, a continuously rotating head, a guide for the insertion of wire to be stripped, and cutting members pivotally hung to swing axially within said head, said members by centrifugal force urged into a plane transverse to the axis of the head, the members axially yielding to the incoming wire but returning to their initial position upon withdrawing the wire and penetrating the insulation while thus returning.

2. In an insulated wire stripper, a continuously rotating head, a guide for the insertion of wire to be stripped, and cutting members pivotally hung within said head, said cutting members maintained radially directed by centrifugal force, free to swing axially under the pressure of a wire inserted through said guide and to return to the radial position upon withdrawal of the wire, the cutting members penetrating the insulation during this return movement.

3. In a wire stripper, a continuously rotating bifurcated head, a wire guide concentrically mounted on the head, cutting members pivotally mounted to swing axially within the bifurcation of the head with

their cutting edges directed toward the axis of the head, and their outer ends sufficiently heavier than their inner ends to cause the centrifugal force to swing them axially into radial position.

4. In a wire stripper, a continuously rotating head, a wire guide, cutting members pivotally hung in said head and having their cutting edges directed toward the axis of the head, said members free to yield axially to the pressure of wire inserted through said guide, but returning to their initial position and simultaneously penetrating the wire insulation upon withdrawal of the wire, and means adjusting said members to the thickness of the wire to be stripped.

5. In a wire stripper, a continuously rotating head, a wire guide, cutting members within the head with their cutting edges directed toward the axis of the head, said members free to swing axially when pressed upon by the wire inserted through the guide but returning to their initial position upon withdrawal of the wire and cutting through the wire insulation during this return movement, and a stationary cover totally enclosing the mechanism described.

6. In a wire stripper, a continuously rotating head, frames pivotally seated in said head, knives adjustably seated in said frames with their cutting edges radially directed toward the axis of the head, said frames free to be turned axially by the wire to be stripped but returning to their initial position upon withdrawal of the wire simultaneously penetrating the wire insulation, means interconnecting said frames for simultaneous rotation, and a stationary cover encompassing the entire mechanism.

7. In a wire stripper, a continuously rotating head, frames pivotally mounted in said head, knives seated in said frames, said frames by centrifugal force maintained radially directed with the cutting edges of the knives near the axis of the head, screws in the outer ends of the frames, said screws engaging slots in the knives for the purpose of adjusting the latter, and means clamping the knives in adjusted position.

In testimony whereof I have hereunto affixed my signature.

LAWRENCE JOHNSON.
